UNITED STATES PATENT OFFICE.

GUSTAV A. GULLICKSON, OF SEATTLE, WASHINGTON.

MECHANICAL TOY.

1,309,572.

Specification of Letters Patent.

Patented July 8, 1919.

Application filed February 6, 1919. Serial No. 275,297.

To all whom it may concern:

Be it known that I, GUSTAV A. GULLICKSON, a citizen of the United States, residing at Seattle, in the county of King and State 5 of Washington, have invented certain new and useful Improvements in Mechanical Toys, of which the following is a specification.

This invention has for its object to furnish an interesting mechanical toy.

The invention consists in the employment of devices resembling railway appliances, and includes a crane for unloading articles from a car.

15 An embodiment of my invention is illustrated in the accompanying drawings, in which—

Figure 1 is a side elevational view in which the crane is shown by full lines in one position and by dotted lines in another position. Fig. 2 is a plan view with the crane in the position in which it is represented in dotted lines in Fig. 1. Figs. 3 and 4 are sectional views through 3—3 and 4—4 of 25 Fig. 1.

In said drawings, 5 represents the rails of an inclined track upon which is mounted a wheeled vehicle or car 6. Extending upwardly from the ends of the car deck 7 are laterally inclined posts 8 and 8¹ carrying a longitudinally disposed bar 9, in proximity to the rear side of the car. Secured to the deck is a second bar 11 from which a number of spaced pins or stops 10 extend toward the longitudinal axis of the car. The bar 11 is, moreover, disposed closer to the axis of the car than the upper bar, to enable groups of magnetic plates 12 placed between the adjacent stops and the posts and against both 35 bars, to be held by the latter in inclined positions, as represented in Fig. 3.

13 represents an arm extending upwardly from the rear of the track and terminating in a finger 13¹ which extends into the space 45 below the upper bar 9 to successively engage the groups 12¹, 12², 12³ and 12⁴ (Fig. 2) of plates, as will be hereinafter more particularly described, for the purpose of enabling the car to advance down the track.

50 Supported by legs 14, preferably resting on said track rails, at a lower elevation than the car, is a stand 15. Extending upwardly from said stand is a post 16 inclined away from said car and formed at its upper end 55 with a laterally extending arm 17.

Provided above the stand 15 is a plat-

form 18 which is inclined, as shown in Fig. 1, and having thereon at or near its lower end a cylindrical superstructure 19 simulating an upright steam boiler. Secured to 60 and extending toward the higher end of the platform 18 from the boiler 19 is a bracket 20 through an aperture in which extends a pin 21 making a pivotal connection with the post arm 17.

65 Disposed in axial alinement with the pin 21 is a second pin 22 extending downwardly from the platform 18 and seated in a step bearing 23 provided on the stand 15. The axes of the pins 21 and 22 are arranged in a 70 plane inclined from vertical, as shown.

To afford rotary movements to the platform 18, it is provided with an arcuate slot 24 through which extends the post 16. Hingedly connected to lugs 25 on the platform 15 and extending from the upper end of the latter is a boom 26 which is connected from near its extremity with the boiler by means of a stay 27 within which is included a spring 28.

80 Connected by a pin 29 to the post arm 17 and at a distance to the rear of the pivotal pin 21, is the end of a rod 30 whose other end 30¹ is provided with an eye through which extends the stay 27 between the spring 28 85 and the connection of the stay with said boom.

Secured to the stay 27 is a block 31 arranged to be engaged by the rod end 30¹ when the boom in swinging approaches a 90 vertical plane extending longitudinally of the stand through the pivotal connections 21 and 22, whereby the outer portion of the stay is effected to cause the extension of spring 28 which thereupon tends to swing 95 the boom toward a plane A—A (Fig. 2), projected through the axes of the pivotal pins 21—22 and the pin 29.

33 represents a magnet depending from the end of said boom.

100 Indicated by 34 in Fig. 4 is provided within the boiler a heavy body, which acts to swing the boiler end of the platform downwardly to accordingly swing the boom and the attached magnet toward and above 105 the car deck.

35 represents a pan disposed at the opposite side of the crane from the car, and is provided with an upwardly extending frame or wicket having a horizontal bar 36 arranged 110 to be encountered by a plate when the crane is swung into its dotted line position in Fig.

1, to cause the plate to be detached from the magnet.

To use the toy, the boom 26 is first swung into its full-line position in Fig. 1, bringing the magnet 33 into contact with the outer plate 12 of the first row of the latter. The attraction of the magnet causes the referred-to plate to be engaged to the magnet so that upon being released by the operator, 10 the boom can swing to carry the plate with the magnet in an arcuate direction opposite to that indicated by arrows $x-x^1$ in Fig. 2, until the plate in striking bar 36, is knocked from the magnet to fall in the pan 35.

15 When this occurs, the boom swings back in the direction of arrows $x-x^1$ to cause the magnet to pick up the next plate in the first row, which in turn is transferred to the pan.

The operation is thus continued until the 20 plates from the first row have been removed from the car 6, whereupon the force of gravity acting on the car causes it to move down the track toward the crane until arrested by the finger 13¹ encountering the second row of plates which are thereby presented in 25 engageable position with respect to the magnet for removal, and so on for the plates in each row.

The power of the weight in the boiler 30 tends to swing the crane into its full-line position in Fig. 1, causing the block 31 to engage against the rod 30, resulting in the end of boom 26 being pushed outwardly by the stay 27 and in opposition to the spring 28. Such outward movement of the boom-end 35 lowers the latter just before the suspended magnet engages a plate. The power of the magnetism thus established, coöperating with the power of the spring, stops the swinging movements of the boom when 40 traveling in the direction of arrows x^1 (Fig. 2) above the car. The energy conserved in the spring, however, coöperating with the resiliency of the boom, is asserted to cause 45 the crane to swing in the opposite direction until the engaged plate is dragged from the car deck; the weight of the suspended plate then contributes to the power of the spring to swing the crane in a direction opposite 50 to arrows x^1 until the axis of the boom and boiler passes the plane A—A, whereupon the momentum of the crane and its load will cause the continuance of the crane's 55 travel until the plate is knocked from the magnet.

Being relieved of the plate, the unbalanced weight of the crane acts in conjunction with the spring 28 to swing the boom into position to enable the magnet to pick 60 up another plate.

The invention will, it is thought, be understood from the foregoing description.

What I claim is—

1. A toy of the character described, consisting of a crane arranged for rotary move-

ments, a magnet depending from the crane boom, a plurality of magnetic articles, a support therefor disposed at one side of the crane, and a device provided at the opposite side of the crane from said support and 70 adapted to be encountered by the articles as they are successively carried by the magnet in the intermittent swinging movements of the crane for effecting the detachment of the articles from said magnet. 75

2. A toy of the character described, consisting of a crane arranged for rotary movements about an inclined axis, a magnet depending from the crane boom, a weight provided on the crane and tending to swing 80 the boom end of the crane into the highest elevation of its revoluble travel, a plurality of magnetic articles, a support therefor disposed at one side of the crane, and a device provided at the opposite side of the crane 85 from said support and adapted to be encountered by the articles as they are successively carried by the magnet in the intermittent swinging movements of the crane for effecting the detachment of the articles from 90 said magnet.

3. A toy of the character described, comprising a stand, a platform mounted thereon for rotary movements about an inclined axis, a boom extending from one end of 95 said platform, a weight supported on said platform at the opposite side of said axis from the boom, tending to swing the platform to carry the boom to the highest elevation of its revoluble travel, a magnet 100 depending from the boom, and resilient means acting in opposition to the power of said weight and tending to successively swing the boom from its highest elevation.

4. In a toy of the character described, a 105 stand, a post extending upwardly therefrom, a platform mounted on said post, for rotary movements about an inclined axis, a boom extending from one end of said platform, a weight supported on said platform 110 at the opposite side of said axis from the boom tending to swing the platform to carry the boom to the highest elevation of its revoluble travel, a magnet depending from the boom, a rod connected to said post, and resilient means coöperating with the rod and 115 acting in opposition to the power of said weight and tending to successively swing the boom from both its highest and lowest elevations. 120

5. In a toy of the character described, an inclined track, a wheeled vehicle mounted on said track, devices provided upon the vehicle for supporting groups of magnetic plates in spaced relations, a revoluble crane 125 carrying a magnet and adapted to successively engage the plates of said groups and remove the same from the vehicle as the latter is advanced, and relatively stationary means engageable with the plates 130

whereby as each group thereof is removed from the vehicle the latter is afforded movement for the vehicle to advance down the track to present the plates of the adjacent group to the magnet.

6. In a toy of the character described, a crane revoluble on an inclined axis and having a boom member, said crane being adapted to be swung by gravity to present the crane boom at the highest elevation of its orbital travel, a magnet depending from the outer end of said boom member, a plurality of magnetic articles, a support for said articles at one side of the crane, and a device provided at the other side of the crane for knocking the articles from the magnet when the boom is swung above said device in conveying the articles from said support.
- 10 7. In a toy of the character described, a crane revoluble on an inclined axis, and hav-

ing a boom member, said crane being adapted to be swung by gravity to present the crane boom at the highest elevation of its orbital travel, a magnet depending from 25 the outer end of said boom member, a plurality of magnetic articles, a support for said articles at one side of the crane, a device provided at the other side of the crane for knocking the articles from the magnet 30 when the boom is swung above said device in conveying the articles from said support, and constraining means coöperating with the weight of said articles for imparting unloading movements of the crane with respect 35 to said support.

Signed at Seattle, Washington, this 27th day of January, 1919.

GUSTAV A. GULLICKSON.
